UNITED STATES PATENT OFFICE.

MILTON H. LUCE, OF KANSAS CITY, MISSOURI, ASSIGNOR TO WHEARY-BURGE TRUNK COMPANY, OF RACINE, WISCONSIN.

LOCKING DEVICE FOR TRUNKS.

Application filed January 17, 1923. Serial No. 613,136.

To all whom it may concern:

Be it known that I, MILTON H. LUCE, a citizen of the United States, residing at Kansas City, county of Jackson, and State of Missouri, have invented new and useful Improvements in Locking Devices for Trunks, of which the following is a specification.

My invention relates to improvements in locking devices for trunks and is particularly applicable to wardrobe trunks of the general type disclosed in Letters Patent of the United States to George H. Wheary, No. 1,134,175, dated April 6, 1915, although it is also applicable to ordinary trunks, such for example, as those disclosed in Letters Patent of the United States to said George H. Wheary, No. 1,158,412, dated October 26, 1915, and to numerous other trunks in common use.

The primary object of this invention is to provide improved means whereby the motion of a movable member associated with a key operated lock may be transmitted to one or more distant locking members to automatically operate the latter, whereby the closing and locking together of the parts of a trunk at one point, will without any attention on the part of the user result in a doweling, binding and locking together of trunk parts at one or more other points.

Further objects of this invention are to provide means whereby motion transmitting mechanism located within one section of a trunk may be utilized to operate locking devices located wholly or partially exterior to the trunk walls;—to provide means whereby auxiliary locking devices, dependent for locking operations upon a movable member associated with a manually operable lock, may be automatically retracted when such movable member is unlocked or retracted;—to provide means whereby the auxiliary locking devices will effectively draw the associated sections of the trunk into binding relation with each other;—to provide auxiliary

locking devices which may be protected by suitable housings located in part upon the interior face and in part upon the exterior face of the associated wall of a trunk section which the housing also reinforces;—to provide means whereby an auxiliary locking device, when released, will initially open or separate the parts controlled thereby; and in general to provide auxiliary locking devices of the above described type which will not only be efficient and durable under conditions of severe use, but which will also be capable of use without reducing the capacity of the trunk, injuring its contents or in any manner interfering with the use of the trunk for any ordinary purpose or the proper packing or unpacking thereof.

As applied to wardrobe trunks, it is an object of my invention to provide means whereby all movable parts of the auxiliary locking mechanism may be mounted upon or in the wardrobe section of the trunk, leaving the interior of the body section wholly free and unobstructed for the reception of packed fabrics or the operation of drawers or other receptacles within which clothing is to be packed. It is well known that the ordinary wardrobe trunk has a body section which is usually subdivided by shelves, drawers or partitions into compartments within which clothing may be packed or within some of which articles may be placed which would be injured by compression or packing. One other section, commonly termed the wardrobe section, is utilized to receive articles of wearing apparel which may be suspended from hangers mounted upon suitable supports at one end of the trunk or section. It is desirable that the body section be wholly unobstructed by any movable or motion transmitting parts or mechanisms for locking the trunk sections together, inasmuch as such parts either occupy space exterior to the drawers or other compartments and thereby reduce the capacity of the trunk body or allow the

articles packed in the trunk body to contact with and be injured by such movable parts. This invention, therefore, contemplates a location of the movable connections for the 5 auxiliary locking devices in the wardrobe section where suspended clothing will bear only lightly against the locking devices even if the latter are exposed.

In the drawings:—

10 Fig. 1 is a vertical sectional view of a wardrobe trunk equipped with my improved locking mechanism, the section being drawn to a plane transverse to that which includes the meeting edges of the body and wardrobe 15 sections.

Fig. 2 is a view of a fragment of the wardrobe section showing my improved locking mechanism applied to one side wall thereof.

20 Fig. 3 is a detail view of the locking lever and associated catch plate.

Fig. 4 is a top view of the locking lever showing the catch in section on line 4—4 of Fig. 3.

25 Fig. 5 is a fragmentary view of the upper end of a wardrobe trunk, partly in elevation and partly in section, showing a slight modification.

Fig. 6 is an elevation of an ordinary trunk 30 illustrating my invention as applied thereto.

Fig. 7 is a similar view showing a slight modification of the structure disclosed in Fig. 6.

35 Fig. 8 is a detail view of the manually controlled portion of the lock operating means employed in the structure disclosed in Fig. 6, the fragment of the side wall of the body portion of the trunk being shown in horizontal section.

40 Fig. 9 is a similar view of the corresponding mechanism employed in the structure disclosed in Fig. 7.

Fig. 10 is a view of the same as seen from the inner side of the trunk wall.

45 Like parts are identified by the same reference characters throughout the several views.

Fig. 1 shows a wardrobe trunk having a body section 1, a wardrobe section 2, and a lid or cover section 3, all organized and arranged substantially as disclosed in said former patent to George H. Wheary, No. 1,134,175. But in place of the locking mechanism disclosed in said patent for holding the lower portions of the wardrobe section and body section together, I employ a locking lever 4 which is fulcrumed at 5 within a housing 6. The housing 6 is provided with end flanges 7 and 8 which are secured to the inner face of the side wall 13 of the wardrobe section and the flange 8 has a semi-cylindrical offset portion 10 which forms a guideway for the vertically disposed operating bar 11 and a partial enclosure 60 for a coiled, compression spring 12, the

lower end of which is anchored to the bottom of the guideway 10 and the upper end of which is seated against a bracket 13 carried by the bar 11.

The lower end of the bar 11 is provided 70 with a slot 14 in which a pin 15 carried by the power end of the lever 4 is loosely engaged. The other end of the lever is offset and positioned within a notch 17 formed in the supporting side wall 13 of 75 the wardrobe section 2 and this offset portion of the lever is provided at its free end with a projecting stud 18, preferably exterior to said section wall, but protected by a housing plate or member 19 which may 80 constitute an extension of the reinforcing corner piece 20.

A housing 19 also forms a doweling pocket to receive a doweling catch plate 22 carried by the opposing wall of the body section 1. 85

This doweling catch plate is provided with a curved slot 23 adapted to receive the stud 18 carried by the lever 4 when said lever is swung to locking position. The outer margin of the slot 23 is so formed that the 90 stud 18 may move with a wedging action thereon when the lever is swung to locking position, thereby drawing the opposing side walls of the wardrobe section and body section into binding pressure contact. The 95 inner wall of the slot 23 is also formed to receive the pressure of the stud 18 while the lever is being swung from locking to unlocking position, whereby said opposing walls may be initially separated during this movement of the locking lever.

The spring 12 tends to hold the bar 11 in a raised position with the inner end of the lever 4 correspondingly raised and the outer or locking end, with the locking stud 18, depressed to releasing position, i. e., to a position with the stud 18 withdrawn from the doweling catch plate 22. The lever 4 is swung to locking position by applying 105 downward pressure to the bar 11 and this downward pressure may be applied by the lid or cover section 3, preferably through a bracket 25 secured to the inner face of said section in a position to bear upon the upper end of the bar 11 and push said bar 110 downwardly when the lid or cover section 3 is swung to closed position. Said lid or cover section may be locked in closed position as disclosed in said former Patent No. 1,134,175, but as no specific locking mechanism is essential it is not deemed necessary to illustrate or describe it. It is obvious 115 that as long as the lid or cover section is closed the bar 11 will be held in its depressed position. And the arrangement is such that when the bar 11 is thus depressed the locking lever 4 will occupy a position substantially as indicated by dotted lines 120 in Fig. 1 with the locking stud 18 near the upper end of the slot 23 in the catch plate 125

130

22, in which position the edges of the wardrobe section of the trunk will be in binding pressure engagement with the meeting edges or margins of the body section.

5 Guide clips 27 and 28 are preferably applied to the side wall 13 of the wardrobe section to hold the rod 11 in operating position.

In Fig. 5 the parts illustrated are identical 10 with those illustrated in Fig. 1, except that the locking bar 11 is made a little longer and the lid section 3 is not provided with the bracket 25. The top of the lid section 3, therefore, bears directly upon the operating piece or bar 11.

In Fig. 6 a trunk is illustrated with a body section 1^a and a cover section 2^a which may be taken as representative of any ordinary trunk in common use. The cover 20 section is locked to the body section by an ordinary key operated lock having a hasp 3^a which corresponds functionally with the lid 3 shown in Fig. 1 so far as the invention herein disclosed is concerned. The hasp 3^a 25 constitutes a swinging member, the motion of which is utilized to actuate the operating piece or bar 11^a through means similar to that disclosed in said former patent to Wheary No. 1,290,445, i. e., through the 30 curved lever arm 35 disclosed in Fig. 8 of the drawings of this application. The hasp is provided with an ordinary locking barrel 39 which, when the hasp is in locking position, bears upon the free end of lever 35 and pushes the lever inwardly. Near its 35 fulcrum the lever bears upon the end of the locking bar 11^a and pushes the same in opposition to the retracting spring 12^a, thereby swinging the locking lever 4^a into locking relation to the doweling catch 22^a.

In the structure disclosed in Fig. 6 the locking lever 4^a directly co-operates with the key operated lock to hold the respective ends of the lid section 2^a in contact with the opposing margins of the body section. One key is, therefore, utilized to lock the lid section to the body section at two widely separated points.

If greater security in the fastening of the lid section is desired, the structure illustrated in Figs. 7, 9, and 10 may be utilized. In these views a trunk is illustrated in which the hasp 3^b is centrally located and the locking barrel 39^b is utilized to actuate two oppositely disposed, curved levers 35^b and 40, respectively. The lever 35^b actuates an operating bar 11^b in exactly the same manner as above described with reference to Fig. 6, whereby the locking lever 4^b near one end of the trunk is actuated to locking position.

The lever 40 similarly, but in the opposite direction transmits motion through a sliding bar 11^c to a locking lever 4^c located near the other end of the trunk disclosed in

Fig. 7. The lid of this trunk is, of course, provided with two doweling catches 22^b and 22^c which are, respectively, engaged by the locking levers 4^b and 4^c.

From the foregoing description of the 70 modified forms disclosed in Figs. 5, 6, and 7, it will be obvious that my invention is not limited to the use of any particular manually operable swinging member for actuating an operating piece or bar, such as 75 the bar 11, to transmit motion to the locking lever. Any member of the trunk, such as the cover 3, which requires to be manually operated or moved when closing the trunk may be utilized to apply the necessary 80 power to the operating piece 11 and transmit motion to the point where a locking engagement is to be automatically effected. However actuated to locking position, it is 85 obvious that my improved locking mechanism is effective to accurately dowel the parts to be locked, draw them together with binding pressure and not only release them when the manually operable member is 90 moved to releasing position, but automatically separate them initially to a sufficient extent to allow the user to grasp the separated margins and to open the body and 95 wardrobe sections of the trunk without difficulty.

As applied to a wardrobe trunk, my invention has the further advantage above noted, viz, that all of the parts are located 100 outside of the body section and all of the movable parts are located within or upon the wardrobe section. Also the locking mechanism per se is located at the lower end 105 of the wardrobe section below the point reached by any but the longest garments to be suspended within said section, these locking parts furthermore being housed in such a manner as to prevent them from catching in the fabric of any clothing contained in said section. The doweling members and the locking stud 18 are located 110 wholly outside of the section so that there is no danger of clothing being caught by the doweling catch 22 and forced into the housing 19 or entangled with the stud 18.

I claim:

1. Trunk locking mechanism comprising the combination with the meeting margins of two trunk sections, of a locking lever fulcrumed to the wall of one section, the adjacent margin of the section being recessed and said lever having an offset portion adapted for swinging movement in said recess, a locking device carried by the offset portion of the lever, and a co-operating catch carried by the registering wall member of the opposing trunk section.

2. Trunk locking mechanism comprising the combination with trunk sections having mating margins, of a fixed catch on the side wall of one section adapted to serve as a

doweling member, a housing on the opposing side wall of the other section adapted to serve as a doweling socket, a locking lever within said last mentioned housing, 5 fulcrumed thereto, and having an offset portion in said doweling socket adapted to engage the doweling catch to lock the latter in said socket.

3. Trunk locking mechanism comprising 10 the combination with trunk sections having mating margins, of a fixed catch on the side wall of one section adapted to serve as a doweling member, a housing on the opposing side wall of the other section 15 adapted to serve as a doweling socket, a locking lever within said last mentioned section, fulcrumed thereto and having an offset portion in said doweling socket adapted to engage the doweling catch to 20 lock the latter in said socket, a distant manually operable member, and motion transmitting connections for utilizing its movement in one direction to actuate said lever to locking position.

25 4. Trunk locking mechanism comprising the combination with trunk sections having mating margins, of a fixed catch on the side wall of one section exterior to the inner surface of the wall, a lever fulcrumed to 30 the opposing wall of the other section and having a projection adapted to engage said catch, an operating piece pivoted to the lever, a manually operable actuating member adapted to move the operating piece in 35 one direction, and means for automatically moving the operating piece in the other direction when relieved of the pressure of the actuating member.

5. In a trunk locking mechanism, the combination with a trunk section wall provided 40 with a recess, of a locking lever fulcrumed adjacent to said recess and having a working end portion offset into said recess and provided with a locking projection, a sliding bar mounted upon the inner face of said section and having slotted pivotal connection with one end of the lever, resilient means for normally holding the bar and lever in unlocking position, and manually operable 45 means for actuating said bar to swing the lever into locking position.

6. In a trunk locking mechanism, the combination with a trunk section wall provided 55 with a recess, of a locking lever fulcrumed adjacent to said recess and having a working end portion offset into said recess and provided with a locking projection, a sliding bar mounted upon the inner face of said section and having slotted pivotal connection 60 with one end of the lever, resilient means for normally holding the bar and lever in unlocking position, manually operable means for actuating said bar to swing the lever into locking position, said manually 65 operable means having a key-controlled lock

adapted to hold the manually operable means and thereby the bar and lever in locking position.

7. Trunk locking mechanism comprising 70 the combination with trunk sections having meeting margins, of a fixed catch on the side wall of one section providing a curved slot, a lever fulcrumed to the opposing wall of the other section and having a projection 75 adapted to engage in said slot, motion transmitting connections for actuating said lever to locking position from a distant point, and a spring for retracting said lever when the actuating pressure is relieved, said slot having curved margins adapted to be engaged by the projection on the lever and so formed as to draw the sections together when the lever moves to locking position and to force them apart to some extent when the lever is moved to unlocking position.

8. In a trunk locking mechanism, the combination with a trunk section wall provided with a recess, of a doweling housing on one side of said recess, a lever housing on the other side of said recess, a lever fulcrumed 80 within the lever housing and having a portion extending into the doweling housing, and another trunk section provided with a catch adapted to enter the doweling housing 85 when the sections are closed together, said catch being adapted to be engaged by said lever.

9. In a trunk locking mechanism, the combination with a trunk section wall provided 90 with a recess, of a doweling housing on one side of said recess, a lever housing on the other side of said recess, a lever fulcrumed 95 within the lever housing and having a portion extending into the doweling housing, another trunk section provided with a catch 100 adapted to enter the doweling housing when the sections are closed together, said catch being adapted to be engaged by said lever, together with a manually operable device 105 for securing said sections together at a point distant from said lever, and means for automatically transmitting motion from the manually operable securing device to move said lever to locking position when the securing device is in securing position.

110 10. Trunk locking mechanism comprising the combination with a trunk having a body section, a wardrobe section, and a lid section 110 adapted to close one end of the wardrobe section, of means exterior to the body section and wardrobe section for doweling and locking said sections together near their lower ends, and lock actuating means within the wardrobe section adapted to be actuated 120 by the lid section into locking position, together with means for automatically releasing the wardrobe section from lock engagement with the body section when the lid section is raised.

125 11. Trunk locking mechanism comprising 130

the combination with a trunk having a body section, a wardrobe section, and a lid section adapted to close one end of the wardrobe section, of a doweling catch projecting from the lower end of the body section, a locking lever fulcrumed at the lower end of the wardrobe section and adapted in one position

to engage the doweling catch, means for transmitting motion from the lid section to said locking lever to move the same into such engagement, and means for automatically retracting the lever when the lid section is swung to open position. 10

MILTON H. LUCE.
